DRAPERY, DRAPERY HEADING, AND
SUPPORTING MEANS THEREFOR

Elizabeth S. Atkins, Asheville, N. C.

Application October 11, 1949, Serial No. 120,756

11 Claims. (Cl. 160—348)

1

This invention relates to draperies, drapery headings, and supporting means therefor.

The making of pinch-pleated drapery headings by conventional methods is quite tedious and time-consuming. Such headings are formed by inserting a strip of crinoline or buckram in the top hem of the drapery and stitching the stiffening material in position. If the stitching is done by machine, the stitches are exposed, and to conceal the stitching, hand sewing is necessary. The pleats and the spaces therebetween are measured and marked with pins, and the heading at each pair of pins is brought together to form the basis of pleats which are stitched by machine. The top edge of the pleat is maneuvered into usually three approximately equal divisions known in the trade as "clover leaves" and they are tacked at one point by hand. The lower edge of the heading is maneuvered into a continuation of the pleat folds and tacked, usually by hand, through all of the eighteen thicknesses of material usually present at the point of tacking. The drapery hook is then sewed to the back of each pleat by hand, a procedure which is slow and tedious even for skilled workers. Pin hooks may be pushed in, but it usually requires substantial care and patience to locate the hooks properly so that the drapery hangs properly, and pins of this type frequently fall out while the draperies are being hung.

If the draperies are not to be hung immediately, storage is a problem, especially in professional drapery workrooms, from which draperies must be delivered in perfect condition. The permanent formation of the pleats makes it difficult to store the draperies and for this reason they are frequently laid out flat on a work table and covered, thus eliminating the table from use during the storing period. When draperies are to be dry-cleaned or washed, the hooks are usually ripped off to prevent tearing the material in cleaning, and then must be re-sewed by hand before the draperies again can be hung.

If pin hooks are used, they are easy to remove, and replacing them is fairly easy, although there is always the danger of pricking the fingers. Moreover, draperies with pin hooks seldom hang evenly, and the hooks are subject to other well-known disadvantages. A good job of pressing is difficult to achieve around the pleats, even for professional cleaners and pressers.

An important object of the present invention is to provide a novel type of heading, or heading stiffening material, which has formed as a part thereof or permanently attached thereto novel

2

means for connecting the drapery supporting hooks.

A further object is to provide a novel drapery heading stiffening material which may be manufactured and sold as long rolled strips which readily may be cut off to desired lengths and attached to the drapery material with the greatest possible ease and simplicity to facilitate the formation of the finished draperies, and particularly 10 pleated draperies, the heading material embodying supporting hook engaging means which greatly facilitate the formation of the pleats.

A further object is to provide a material of the character referred to wherein the drapery hook 15 engaging means are so formed relative to each other as to facilitate greatly the formation of the inner folds of the pleats and wherein the hook engaging means, when the folds are brought into proper relationship, are arranged in vertical 20 alignment whereby all are adapted to receive a single shank of a novel type of drapery hook.

A further object is to provide a novel drapery heading embodying the stiffening material referred to whereby pinch-pleated finished draperies may be quickly and easily made and whereby the draperies may be quickly and accurately 25 hung and supported in proper position with the pleats held upright without any sagging or unevenness.

A further and important object of the invention 30 is to provide a drapery heading which lends itself readily to use either as stationary draperies or draw curtains and wherein the pleats are easily formed and easily removed to flatten the curtain for storage and ironing.

A further object is to provide in combination 35 with the heading structure a novel supporting hook which serves to hold the pleats of each group in proper form and which are easily removed to flatten the pleats when desired and which is frictionally held in place against accidental removal while the drapery is being handled.

A further object is to provide an assembly of 40 elements in a pleated drapery which particularly facilitates the making of pinch pleats by providing a novel form of clip for this purpose, thus enabling inexperienced homemakers to make and hang drapes which are beautifully professional in appearance.

A further object is to provide a novel type of 45 end hook engaging means for the finished drapery whereby the end of the drapery may be easily hung in proper relationship to the supported pleated portions of the drapery.

Other objects and advantages of the invention will become apparent during the course of the following description.

In the drawing, I have shown several embodiments of the invention. In this showing,

Figure 1 is a fragmentary perspective view of a portion of a partially formed drapery employing a heading stiffening member embodying the present invention.

Figure 2 is a similar view of the same, showing a plurality of the pleat folds partially assembled.

Figure 3 is a similar view of the same, showing a completed pleat with a supporting hook therefor in position.

Figure 4 is a fragmentary perspective view of a portion of the upper end of a drapery looking from the outside thereof and showing completed pleats as they will appear in the room, if a pinch clip is employed.

Figure 5 is a face view of a heading hook adapted for use with the drapery.

Figure 6 is a similar view of a drapery hook adapted for supporting the drapery.

Figure 7 is a fragmentary perspective view of a modified form of heading stiffening material, and

Figure 8 is a perspective view of a pinch pleat clip adapted for use with the invention in forming the highly desirable pinch pleats illustrated in Figure 4.

Referring to Figure 1, the numeral 10 designates a strip of stiffening material which preferably is made in long strips and sold in rolled form to be cut off in lengths. The material 10 is preferably crinoline, buckram or some similar relatively stiff form-retaining fabric commonly used in making headings for draperies. At spaced points along the material, there are printed lines 11, 12, 13 and 14, preferably in the form of spaced dots as shown in Figure 1 to form pleat fold guide lines in a manner to be described. Printed or otherwise applied near and parallel to the lower edge of the strip 10 is a similar line 15, the purpose of which also will be described below. Adjacent and parallel to the upper edge of the strip is also printed a similar line 16, preferably of dots, to act as a guide in attaching the body of the drapery material indicated by the numeral 17. The inner surface of the strip 10 between the line 16 and the top edge of the strip is provided with a suitable adhesive 18 for positioning the drapery material 17 relative to the strip 10 prior to the stitching of the edge of the drapery material 17 in a manner to be described.

A plurality of hook-engaging elements are embodied with or attached to the strip 10 at the lines 11 to 14 inclusive. These elements may be woven as a part of the strip 10 or they may be separately formed and attached thereto in any desired manner. In the present instance, the attaching or supporting elements have been shown as formed of stiff fabric sewed to the strip 10. The arrangement of these elements is subject to great variation, and it will become apparent that the arrangement shown in Figure 1 is purely illustrative.

Referring to Figure 1, the numerals 22 and 23 designate supporting elements attached to the strip 10 along the line 11, while similar elements 24 and 25 are attached to the strip 10 along the line 14. Each of the elements 22 to 25 inclusive is relatively short vertically, and each is bent to form a pin shank receiving loop 28 and tabs 29 projecting therefrom whereby each of the ele-

ments referred to may be stitched as at 30 for attaching the elements to the strip 10 along the lines 11 and 14. The tabs 29 are somewhat exaggerated and need be only sufficiently wide to prevent the stitches 30 from pulling out. Along the lines 12 and 13 are attached similar but relatively longer attaching elements 32 and 33. These elements are stitched as at 34 to form them into loops 35 to receive the pin shank referred to below. The elements 32 and 33 are stitched to the strip 10 along the lines 12 and 13 respectively along lines 36, spaced from the lines 34 for a purpose to be described. It will be noted that all of the supporting elements 22 to 25 and 32 and 33 are offset vertically from each other, and accordingly these elements have the loop portions thereof adapted to be brought into vertical alignment as shown in Figure 3. It will become apparent that in order to assemble the loops of the supporting elements in the manner referred to, they must be not only vertically offset but of such relative lengths as not to overlap vertically.

The lines 11 to 14 inclusive and their associated supporting elements are repeated at intervals along the strip 10 throughout the roll of such material. In the spacing of the lines 11 to 14 of each group from each other and the spacing of each group of such lines from the next adjacent groups are matters of choice. In practice, for average drapery installations, it is preferred that the repetition of the lines 11 to 14 inclusive occur every eight inches on centers. It is further preferred that each line 11 be spaced four inches from the line 14 of the associated groups of four lines. Therefore, each line 14 will be arranged preferably four inches from the line 11 of the next adjacent repeated pattern.

In forming a unit strip 10 for a given drapery, the strip will be cut approximately along one of the lines 11 (or along one of the lines 14) depending upon the vertical edge of the drapery from which the arrangement of the strip 10 is started, and in Figure 1, the edge of the strip has been cut adjacent a line 11 to eliminate the adjacent supporting elements 22 and 23 and leave the strip 10 with a free edge. To such edge is attached a preferably preformed supporting element 40 formed of the same material as the supporting elements previously described, but of a length approximately corresponding to the vertical distance between the lines of dots 15 and 16, if the pinch clip to be described is not used. The supporting element 40 is preformed with a pin shank receiving loop 41 by stitching the element 40 along the line 42. The element 40 is then stitched to the free end of the strip 10, for example along the line 43, and it will become apparent that this is done prior to the attaching of the drapery material 17 to the strip 10 in the manner to be described. The end of the strip 10 to which the supporting element 40 is secured will be at the inner edge of the finished drapery, and the outer edge will be preferably treated in the same manner.

Before being attached to the drapery 17, the strip 10, in accordance with the foregoing description, will be a complete finished unit ready for attachment to the drapery. What will be the upper edge of the drapery is turned over as at 50 to form a hem stitched to the body of the drapery as at 51. The edge of the hem 50 will be straight, and with the strip 10 lying on a suitable table, the drapery will be arranged above the strip with the hemmed edge 50 overlapping the upper edge 75 of the strip 10 and with the drapery 17 project-

ing upwardly from the strip 10. The hemmed edge 50 will then be aligned with the line of dots 16 and pressed down against the adhesive 18, thus forming a temporary attachment between the drapery body and strip 10 to facilitate the stitching of the drapery to the upper edge of the strip 10 as at 52 (Figures 2 and 3). After the parts have thus been stitched together, the body of the drapery is dropped down over the front face of the strip 10, that is, the face of the strip remote from the face shown in Figures 1 and 2. The lower edge portion of the strip 10 is then anchor-stitched to the body of the drapery along the short sections of the lines of dots 11 to 14 inclusive between the line 15 and the lower edge of the strip 10, as indicated by the numeral 53 in Figure 2. The body of the drapery, when located in position relative to the strip 10, will have what will be its inner vertical edge 54 (Figure 1) projecting somewhat beyond the supporting element 40 and the adjacent end of the strip 10. At any convenient time, this edge may be turned inwardly to form a hem 55 (Figure 2) stitched to the body of the drapery as at 56. The outer edge of the drapery will be similarly finished, and assuming that the bottom edge of the drapery has been hemmed to proper length, the drapery will now be ready for the forming of the pleats and the hanging of the drapery on the rod or other supporting structure.

Particular types of supporting hooks are employed in connection with the header structure described above, two of such hooks being shown in Figures 5 and 6. In Figure 5, there is illustrated a heading hook indicated as a whole by the numeral 60. This hook has a straight inner shank 61, the upper end of which is preferably pointed to facilitate its insertion through the loops 28 and 35. At the lower end of the shank 61, the hook is bent in a sharp loop 62 and then extends upwardly a short distance as at 63 parallel and in close proximity to the lower end of the shank portion 60. Above the portion 63 the hook bulges outwardly as at 64 and above such bulged portion the hook has a section 65 parallel to and normally contacting with the shank 61. The upper end of the hook terminates in a hook element 66, the high point 67 of the inside of which is spaced a substantial distance from the shank 61. The heading hook is used where the track from which the drapery is suspended is placed relatively close to a wall, the hook element 66 engaging the track at a point 67, thus spacing from the wall a header which will be carried by the shank 61 in the manner to be described.

In Figure 6, I have shown a drapery hook adapted for use with tracks or rods where it is desired that the drapery lie close to the rod. This hook is indicated as a whole by the numeral 70, and except as noted below, this hook is very similar to the hook shown in Figure 5, and the parts common to the two hooks have been indicated by the same reference numerals. In Figure 6, the hook is provided with an upper hook element 71 slightly different from the hook 66 previously described in that the highest point 72 within the hook lies close to the shank 61 so that the draperies will lie close to the rod which will be arranged within the hook element 71.

In Figure 8, I have shown a pinch clip adapted for use when it is desired to form pleats into pinch pleats such as are commonly made professionally. The clip is indicated as a whole by the numeral 75 and is formed of a strip of relatively stiff resilient material looped as at 76 intermed-

iate its ends to form arms 77 having their free ends 78 converging and opening slightly at their extremities to facilitate entrance into the group of pleat folds in a manner to be described.

As previously stated, the hook shank receiving loops may be of any desired type to accomplish the results more fully set forth below. For example, the loops shown in Figure 1 may be attached as described or woven as an integral part of the strip 10. The loops in Figure 1 are so formed and proportioned as to lie in end to end relation when the pleat folds are completed and the parts assembled. Thus the loops in effect are continuous between the lines 15 and 16, and while this is desirable for permanence in maintaining the perfectly upright shape and position of the strip 10, such arrangement is not essential and a modification of the loop formation is shown in Figure 7.

Referring to Figure 7, the numeral 80 designates a crinoline or buckram strip corresponding to the strip 10 without the loops shown in Figure 1, the strip bearing the same lines of dots which have been indicated by the same reference numerals. The strip 80 is provided along the lines 11, 12, 13 and 14 thereof with hook shank engaging loops of an entirely different type from those previously described but intended to perform the same function. These loops are indicated by the numeral 81 and it will be noted that all four of the bottom loops are approximately at the same level, for a purpose to be described. The remaining loops on each of the vertical lines may be arranged at any desired points, but preferably each has a loop near the top and at least one loop between the top and bottom. The loops 81 may be cords or metal rings clasped through the material of the strip 80, or each may be made up of one or more of the longitudinal threads of which the strip 80 is woven.

Operation

The making and hanging of the drapery will be mostly apparent from the foregoing description. A strip of the material 10 is cut to the proper length and provided with the end loops 40, whereupon the upper hemmed edge 50 of the drapery body is pressed over the adhesive 18 with the edge of the hem coinciding with the line 16. The hem 50 is then stitched to the strip 10 as at 52, whereupon the drapery body 17 is dropped down the front face of the strip 10 to its normal position relative thereto at the side of the strip 10 opposite the face shown in Figures 1, 2 and 3. The anchor stitchings 53 are then applied, and either before or after the latter operation, the hem 55 (Figure 2) is stitched to the end of the strip 10. The same operation is performed at the opposite edge of the drapery, whereupon the pleats are adapted to be formed. Assuming that pinch pleats are to be made, the heading of the drapery will be bent along the lines 12 and 13 to provide inwardly extending folds. When these folds are brought together, the supporting elements 32 and 33 lie in adjacent end to end relation. The lower ends of the folds thus formed are pinched together and the clip 75 is slipped over the two folds, as shown in Figure 2, just below the line 15. The top edge of the clip will therefore lie below the horizontal plane of the lower extremity of the supporting element 25.

The heading is then folded similarly on the lines 11 and 14, in which case the supporting elements 22 to 25 inclusive will be brought into vertical alignment with the supporting elements 32

and 33, as shown in Figure 3. The upper extremity of the straight shank 61 of either type of hook shown in Figures 5 and 6 is then inserted through the loop 76 of the clip 75, if such clip is used, then into the loop of the supporting element 25 from the bottom thereof, and then successively through the loops of the supporting elements 23, 33, 32, 24, and 22. When the shank 61 has been pushed upwardly through the loops to its uppermost limit of movement, the loop 25 will rest on the clip 75 and such clip will be at the bottom of the shank 61, with the bottom edge of the clip engaging the sharp bend 62 to be supported thereby while being held in position by the adjacent hook portion 63. The various loops are made of relatively stiff material and their stiffness may be increased, if desired, by immersing them in some suitable coating composition such as shellac. The weight of the adjacent pleated portion of the drape will then be supported by the clip 75. It is not necessary to sew the pleat folds together, since all of the inner pleat folds will be held securely in position by the hook shank 61. The pleat thus formed will appear as shown in Figure 4, each of the completed pleats being indicated as a whole by the numeral 85.

Each of the pleats is formed and held in position in the same manner. The shank 61 of one of the hooks is inserted in the loop 41 at each vertical edge of the drapery, the lower edge of each supporting element 41 engaging the sharp bend 62 at the bottom of the hook. Hooks of the same size and type will be used throughout the drapery, and accordingly all of the supporting bends 67 or 72 of the hooks will be equidistantly spaced from the top of the drapery. These hooks are then engaged with the supporting rod or with any elements carried by the rod or other support for this purpose. When the drapery is so hung, the top edge will be perfectly straight; all of the pleats will match relatively perfectly; the pleats will be equidistantly spaced, and all will be supported in a perfectly upright position. There will be no unevenness or sagging of any part of the drapery. Assuming that the pinch clip 75 has been used, the pleats will appear as shown in Figure 4, tapering to decrease in width downwardly to the region of the clip and then flaring outwardly beneath such clip. This is a highly desirable type of pleat much sought after by homemakers and usually satisfactorily provided only in professional workrooms. The present invention permits any relatively inexperienced homemaker to make and hang draperies with headings which have a highly professional appearance. At the same time, this heading is a great asset to professional drapery workrooms.

In the form of the invention shown in Figure 7, the same procedure is followed as before, except that vertically elongated supporting loops are not employed. The ring-like loops in Figure 7 are wholly satisfactory, the stiffness of the material of the strip 80 being depended upon to prevent sagging or bulging of the material between the vertically spaced loops 81 of each of the vertical lines 11 to 14 inclusive. It is desirable when such form of loops is employed to provide one of the loops in close proximity to the horizontal line 15 at each of the fold lines 11 to 14 inclusive. When such bottom loops are employed, all of them will be receivable in the narrow space inwardly of the hook portion 63, each loop except the bottom one being supported on the next adjacent lower loop and the lowermost loop being supported by the bottom of the hook if the clip 75 is not used.

This arrangement is advantageous in that it distributes the weight of each pleated portion of the drapery equally along the lines 11 to 14 inclusive.

The folds are formed with the strip 80 of Figure 7 in the same manner as previously described, the heading being bent inwardly along the lines 11 to 14 inclusive to bring all of the loops 81 into vertical alignment. Of course, it is not necessary that all of the loops be in perfect vertical alignment before the hook shank 61 is inserted. It is sufficient that the folds be formed and the hook shank inserted through the four lowermost loops 81, after which the remaining loops can be picked up one at a time as the shank 61 is moved vertically upwardly. It is for this reason that the loops 81, other than the lowermost ones, are staggered so as to facilitate the successive picking up of the loops by the shank 61.

It will be apparent that any size hook 60 or 70 may be employed, depending upon the type of supporting rod or the like and the height at which it is desired to support the upper edge of the drapery relative to the supporting rod. The pinch clip 75 need not be employed unless desired, but as suggested above, most homemakers desire draperies formed with pinch pleats.

The construction involves quite a number of highly important advantages, most of which will be apparent from the foregoing description. Particular attention is invited to the fact that a homemaker may buy the strips 10 or 80 by the yard with the supporting loops already attached, except for the end loops. The homemaker need attach only the end supporting loops 41, and it is quite simple for her to stitch the drapery hems 50 and 55 to the strip 10 and to provide the anchor stitching 53. The stitching 52 is done with the body of the drapery extending upwardly from the strip 10, and the stitching 52 accordingly will not show on the right side of the drapery. It is not necessary to tack the pleats or to sew the hooks to the draperies. It is quite easy to bend the pleat folds and insert the shanks of the hooks in the supporting loops, and the number of operations required in the making of a completed drapery is much smaller than the number of operations commonly performed. Accordingly, much time is saved in the making of the draperies.

No problem is involved in the storing of the draperies since it merely is necessary to withdraw the shanks of the supporting hooks, whereupon the heading is free to assume a perfectly flat shape for storage. Accordingly, if the draperies are made in a shop or factory, one may store the draperies without using valuable table surfaces, until he is ready to install the draperies. The complete releasing of the pleats is also highly advantageous when it is desired to wash or clean the draperies. The hooks may be released without cutting any stitchings, and the draperies may be readily ironed perfectly flat. Thereafter, the draperies may be stored until ready for hanging, perhaps the next season, and the operation described above is repeated as to the folding of the heading and the inserting of the hooks in position.

It also will be particularly noted that a homemaker need not do any measuring or use any particular care in forming the pleats. No trial and error is necessary to achieve uniformity in the pleats since it merely is necessary to fold the heading on the lines marked on the stiffening strips as purchased in the stores, and accordingly, the pleats may be formed in a frac-

tion of the time previously required. It is not necessary to measure and mark the fold lines with pins or the like.

As previously stated, the end attaching element 40 at each end of the drapery has its lower end terminating at the line 15 if no pinch clip 15 is employed. In such case, the hooks associated with the pleats will have their lower extremities engaging the loops of the elements 25 and the termination of each end element 40 at the line 15 will provide for the reception of a hook shank 61 with the hook moving upwardly to a level corresponding to the position of each hook employed with the pleats. Where a pinch clip is employed, each end element 40 extends to the lower extremity of the stiffening strip, as shown in Figures 1 and 2, in which case the end hooks will correspond in position to all of the remaining hooks. Thus, in either case, the top edge of the drapery will be supported horizontally.

The types of hooks shown in Figures 5 and 6 particularly cooperate with the drapery heading. As previously stated, each hook portion 63 is biased toward the associated straight shank 61 and when each hook is inserted in position, at least one loop will be frictionally gripped between the associated hook portions 61 and 65. This action frictionally holds each hook against accidentally falling out of position while the draperies are being handled prior to hanging. Moreover, the gripping action referred to greatly assists in supporting the stiffening material in vertical position at each of the pleats and at each end loop 40.

The use of the bulged portions 64 of the hooks also is advantageous. This bulged portion assists in providing the hooks with a highly desirable degree of resiliency to accomplish the gripping action referred to. Moreover, the outward springing of each hook portion 65, when placed in position, is accommodated by the bulged portion of the hook with minimum tendency to spread the hook portion 63 outwardly, thus preserving the function of the close lower hook portions 61 and 63 for snugly receiving the loop 16 of the clip or the loop of the lower supporting element 25. Thus two gripping actions are provided with respect to each hook properly to support the weight of the drapery and to preserve the vertical form of the heading.

I claim:

1. In a drapery heading, a drapery body, a stiffening strip fixed to said body against the inner face of the upper edge portion thereof, and horizontally spaced groups of loops projecting from the inner face of said strip, the loops of each group being vertically offset whereby, when the strip is folded vertically on lines coincident with the respective loops, said strip and said drapery body will be formed in outwardly extending pleats with the loops of each group in vertical alignment, said strip being folded as indicated to bring the loops of each group into vertical alignment and a supporting hook having a straight upwardly extending shank inserted through the aligned loops of each group and serving to hold them in aligned position and maintain said strip folded along said lines.

2. In a drapery heading, a drapery body, a stiffening strip fixed against the inner face of 70 said drapery body adjacent the upper edge thereof, said strip having horizontally spaced groups of vertical indicating lines thereon, at least one loop carried by said strip coincident with each of said lines, the lines of each group being hori-

zontally spaced apart and the loops of each group being so arranged along the associated lines that when the strip is folded along the lines of each group, the loops of such lines may be brought into vertical alignment and the drapery body between said lines will be extended outwardly to form pleats, said strip being folded as indicated to bring the loops of each group into vertical alignment and a supporting hook having a straight upwardly extending shank inserted through the aligned loops of each group and serving to hold them in aligned position and maintain said strip folded along said lines.

3. In a drapery heading, a drapery body, a stiffening strip fixed against the inner face of 15 said drapery body adjacent the upper edge thereof, said strip having horizontally spaced groups of vertical indicating lines thereon, at least one loop carried by said strip coincident with each 20 of said lines, the lines of each group being horizontally spaced apart and the loops of each group being so arranged along the associated lines that when the strip is folded along the lines of each group, the loops of such lines may be brought into vertical alignment and the drapery body between 25 said lines will be extended outwardly to form pleats, said strip being folded as indicated to bring the loops of each group into vertical alignment and a supporting hook having a straight upwardly extending shank inserted through the 30 aligned loops of each group and serving to hold them in aligned position and maintain said strip folded along said lines, said strip having a guide line spaced from and parallel to the lower edge 35 of the strip, one loop associated with each group of lines having its lower extremity substantially coincident with said guide line and each hook having a bend at the lower extremity of the shank thereof engageable against the bottom of said one 40 loop of each group whereby all of the hooks will be in horizontal alignment.

4. In a drapery heading, a drapery body, a stiffening strip fixed against the inner face of 45 said drapery body adjacent the upper edge thereof, said strip having horizontally spaced groups of vertical indicating lines thereon, at least one loop carried by said strip coincident with each 50 of said lines, the lines of each group being horizontally spaced apart and the loops of each group being so arranged along the associated lines that when the strip is folded along the lines of each group, the loops of such lines may be brought into 55 vertical alignment and the drapery body between said lines will be extended outwardly to form pleats, said strip being folded as indicated to bring the loops of each group into vertical alignment and a supporting hook having a straight upwardly extending shank inserted through the aligned loops of each group and serving to hold 60 them in aligned position and maintain said strip folded along said lines, said strip having a guide line spaced from and parallel to the lower edge of the strip, one loop associated with each group of lines having its lower extremity substantially coincident with said guide line and each hook having 65 a bend at the lower extremity of the shank thereof engageable against the bottom of said one loop of each group whereby all of the hooks will be in horizontal alignment, each vertical line extending to the lower extremity of said stiffening strip and the latter being anchor stitched to said drapery body along each vertical line between said guide line and the lower extremity of said strip.

5. In a drapery heading, a drapery body, a

stiffening strip fixed against the inner face of said drapery body adjacent the upper edge thereof, said strip having horizontally spaced groups of vertical indicating lines thereon, at least one loop carried by said strip coincidental with each of said lines, the lines of each group being horizontally spaced apart and the loops of each group being so arranged along the associated lines that when the strip is folded along the lines of each group, the loops of such lines may be brought into vertical alignment and the drapery body between said lines will be extended outwardly to form pleats, said strip being folded as indicated to bring the loops of each group into vertical alignment and a supporting hook having a straight upwardly extending shank inserted through the aligned loops of each group and serving to hold them in aligned position and maintain said strip folded along said lines, said strip having a guide line spaced from and parallel to the lower edge of the strip, one loop associated with each group of lines having its lower extremity substantially coincident with said guide line and each hook having a bend at the lower extremity of the shank thereof engageable against the bottom of said one loop of each group whereby all of the hooks will be in horizontal alignment, and a pinch clip receiving a plurality of the folds formed along the vertical lines of each group, said pinch clip lying wholly below said guide line and having a loop through which the shank of said hook extends.

6. For use in making a drapery heading, an elongated strip having a plurality of groups of loops projecting from the inner face of the strip, each of said groups comprising loops spaced apart longitudinally of the strip and offset transversely of the strip in a manner such that when the strip is folded along transverse lines corresponding to the location of the various loops, the openings in such loops will be in transverse alignment, and said groups being longitudinally spaced apart a distance greater than the longitudinal spacing between adjacent ones of said loops of each group.

7. For use in making a drapery heading, an elongated strip having longitudinally spaced groups of transverse indicating lines thereon, and at least one loop carried by said strip coincidental with each of said lines, the lines of each group being longitudinally spaced apart and the loops of each group being so arranged along the associated lines that folding of the strip along the lines of each group will bring the loops of such lines into transverse alignment.

8. For use in making a drapery heading, an elongated strip having longitudinally spaced groups of transverse indicating lines thereon, and at least one loop carried by said strip coincidental with each of said lines, the lines of each group being longitudinally spaced apart and the loops of each group being so arranged along the associated lines that folding of the strip along the lines of each group will bring the loops of such lines into transverse alignment, said strip having a guide line spaced from and parallel to a longitudinal edge of the strip, one loop associated with each group of lines having its outer extremity substantially coincident with such guide line.

9. For use in making a drapery heading, an elongated stiffening strip having longitudinally spaced groups of transverse indicating lines thereon, and at least one loop carried by said

strip coincidental with each of said lines, the lines of each group being longitudinally spaced apart and the loops of each group being so arranged along the associated lines that folding of the strip along the lines of each group will bring the loops of such lines into transverse alignment, said strip having a guide line spaced from and parallel to a longitudinal edge of the strip to act as a guide in securing the drapery to the strip, all of said loops lying inwardly of such guide line, said strip having adhesive applied thereto between said guide line and the outer edge of the strip to act as temporary securing means for the drapery prior to the permanent securing thereof to said strip.

10. For use in making a drapery heading, an elongated stiffening strip having longitudinally spaced groups of transverse indicating lines thereon, and at least one loop carried by said strip coincidental with each of said lines, the lines of each group being longitudinally spaced apart and the loops of each group being so arranged along the associated lines that folding of the strip along the lines of each group will bring the loops of such lines into transverse alignment, said strip having a guide line spaced from and parallel to one longitudinal edge of the strip to act as a guide in securing the drapery to the strip, all of said loops lying inwardly of such guide line, such strip having a further guide line spaced from and parallel to the other longitudinal edge of the strip, one loop associated with each group of lines having its outer extremity substantially coincident with such other guide line.

11. For use in making a drapery heading, an elongated stiffening strip of substantial width having longitudinally extending guide lines spaced from and parallel respectively to the opposite longitudinal edges of the strip, groups of transverse indicating lines on said strip, the lines of each group being longitudinally spaced from each other and each group of lines being substantially spaced longitudinally from the adjacent group of lines, and at least one transversely elongated loop carried by said strip coincident with each line of each group, said loops being formed of relatively stiff material and the loops of each group being transversely offset from each other whereby, upon the folding of said strip along said indicating lines, said loops of each group may be brought into transverse alignment, the outer extremity of the outermost loop of each group with respect to one of said longitudinally extending guide lines being substantially coincident with such guide line.

ELIZABETH S. ATKINS.
